UNITED STATES PATENT OFFICE.

JAMES R. PUTNAM, OF WATERBURY, CONNECTICUT, ASSIGNOR TO WATERBURY CLOCK CO., OF WATERBURY, CONNECTICUT, A CORPORATION.

INTERMITTENT-ALARM CLOCK MOVEMENT.

1,416,870.

Specification of Letters Patent. Patented May 23, 1922.

Application filed June 16, 1921. Serial No. 477,917.

To all whom it may concern:

Be it known that I, JAMES R. PUTNAM, a citizen of the United States, residing at Waterbury, in the county of New Haven 5 and State of Connecticut, have invented a new and useful Improvement in Intermittent - Alarm Clock Movements; and I do hereby declare the following, when taken in connection with the accompanying drawings, and the characters of reference marked thereon, to be a full, clear, and exact description of the same, and which said drawings constitute part of this application and represent, in—

15 Fig. 1 a view in front elevation of an intermittent-alarm clock movement embodying my invention, parts of the time and alarm trains being omitted for clarity.

Fig. 2 an edge view thereof.

20 My invention relates to improvement in intermittent-alarm clock movements, the object being to provide, at an almost negligible cost, simple and reliable means for eliminating the constant clicking noise resulting 25 from the riding of the intermittent-alarm lever over the intermittent-alarm wheel and the consequent drag upon the time-train, characteristic of ordinary intermittent-alarm clock movements, as now made.

25 With these ends in view, my invention consists in the employment of a cut-out lever mounted upon the staff of the intermittent-alarm lever in position to be engaged by the inwardly-turned, beveled finger at the free 30 end of the alarm-release spring, which is operated by the movement of the alarm-cam wheel upon its staff. My invention further consists in certain details of construction as 35 will be hereinafter described and pointed out 40 in the claim.

In carrying out my invention, as herein shown, I mount a cut-out lever 5 upon the forward end of a rock-shaft 6 journaled between the front-movement plate 7 and the 45 rear-movement plate 8 of the movement. Near its rear end the said shaft 6 mounts the intermittent-alarm lever 9 formed with a long, bowed arm 10 having a beveled nose 11 coacting with the teeth of the intermittent- 50 alarm wheel 12, which, as shown, is mounted upon the arbor 13 of the third wheel 14 of a time-train of any approved construction and not otherwise illustrated. The said lever 5, as thus arranged, close to the inner 55 face of the front-movement plate, is normally

engaged and lifted by the beveled upper edge of the inwardly-turned finger 15 of the alarm-release spring 16, which is secured by a rivet 17 to the front face of the front-movement plate, the said finger extending 60 inwardly through a clearance-opening 18 in the said plate. The beveled upper edge of the said finger also coacts in the usual manner with the alarm-cut-out wire or hammer-tail 19, mounted in the verge-arbor 20, also 65 mounting the verge 21 and the hammer-wire 22 of the hammer 23.

The said alarm-release spring 16 is normally held in its inwardly-sprung position by means of the hub 24 of the slidable alarm-cam wheel 25, the forward face whereof mounts the alarm-cam 26, which coacts with a finger 27 upon a collet 28 mounted upon the forward end of the alarm-set shaft 29, the projecting rear end of which is furnished 75 with a button 30.

The intermittent-alarm lever 9 is provided, as usual, with a stop-arm 31 coacting with a stop-pin 32 in the crown-wheel 33.

It will be seen from the foregoing description and the accompanying illustrations, that the intermittent - alarm mechanism shown and described is of a well-known construction except for the addition to it of the cut-out lever 5 arranged to be operated upon by the 80 alarm-release spring without interfering with the coaction thereof in the usual manner with the alarm-cut-out wire or hammer-tail.

In the operation of my improved intermittent-alarm clock movement, the beveled upper edge of the finger 15 engages with and lifts the cut-out lever 5 and rocks the shaft 6, so as to lift the nose 11 of the arm 10 of the intermittent-alarm lever just above the 95 teeth of the alarm-wheel 12, leaving the same entirely free to normally rotate under it without contact, whereby the objectionable clicking noise produced by the dropping of the nose 11 off the teeth of the wheel 12, as 100 the same rotates under it, as well as the drag upon the time-train, is avoided. However, as soon as the alarm-train is released in the usual manner by the dropping of the finger 27 of the collet 28 into the deep notch of 105 the alarm-cam 26, the spring 16 springs forward and so removes its beveled finger 15 from engagement with the lever 5 and the hammer-tail 19. The nose 11 of the arm 10 of the lever 9 is then allowed to descend 110

into operative position with respect to the teeth of the intermittent-alarm wheel 12, above which the nose 11 of the arm 10 is again raised as soon as the beveled finger 5 of the spring 16 is forced inwardly under the cut-out lever 5, so as to lift the same and rock the shaft 6, as described.

By the simple addition of the lever 5, I am thus able, without other change, to overcome one of the objections to an intermittent-alarm clock movement of the character to which my invention relates.

I claim:

In an intermittent-alarm clock-movement, 15 the combination with the front and rear movement-plates thereof, of an alarm-release spring secured to the front face of the front movement-plate and having its free end beveled and extended rearwardly there- 20 through, a rock-shaft pivoted between the said front and rear movement-plates, an intermittent-alarm lever mounted upon the said rock-shaft at the rear end thereof, adjacent to the forward face of the rear movement- 25 plate, an intermittent-alarm wheel driven by

the time-train and co-acting with the end of the said lever, a verge-arbor pivoted between the said plates at a point close to the said rock-shaft, a verge mounted upon the said verge-arbor near the rear end thereof, a hammer-tail mounted in the said verge-arbor in position to co-act with the beveled end of the said alarm-release spring, and an alarm cut-out lever mounted upon the forward end of the said rock-shaft at a point closely adjacent to the rear face of the front movement-plate in position to engage with the beveled end of the said spring at a point forward of the engagement therewith of the said hammer-tail and operating to normally hold the 40 said rock-shaft in position to maintain the intermittent alarm-lever out of engagement with the intermittent alarm-wheel.

In testimony whereof, I have signed this specification in the presence of two subscr- 45 ing witnesses.

JAMES R. PUTNAM.
